UNITED STATES PATENT OFFICE.

ARTHUR ALLTREE, OF MANCHESTER, ENGLAND.

SLIDE-VALVE INTERNAL-COMBUSTION ENGINE.

1,262,158.

Specification of Letters Patent.

Patented Apr. 9, 1918.

Application filed March 31, 1915. Serial No. 18,246.

To all whom it may concern:

Be it known that I, ARTHUR ALLTREE, a subject of the King of England, residing at 279 Wilmslow road, Fallowfield, Manchester, in the county of Lancaster, England, engineer, have invented certain new and useful Improvements in or Relating to Slide-Valve Internal-Combustion Engines, of which the following is a specification.

10 My invention relates to improvements in four-stroke cycle internal combustion engines, of the type in which the inlet and exhaust ports of the cylinder are controlled by separate segmental or half-cylindrical 15 slide valves, so arranged that each valve operates on both its upstroke and its down-stroke.

I will further describe my invention with the aid of the accompanying sheets of explanatory drawings, in which:—

20 Figure 1 is a longitudinal section of a water cooled engine, and

Fig. 2 is an elevation, partly in section.

25 Fig. 3 is a side elevation of the base of the cylinder and the lower end of the valve cover.

Fig. 4 is a sectional plan showing the valves, valve cover, and vertical flanges.

30 Fig. 5 is an elevation, partly in section, showing the application of the invention to a single cylinder engine.

In the several views like characters of reference denote like or equivalent parts wherever they occur.

35 Referring to the drawings, but first more particularly to Figs. 1 to 4, 1 indicates a stationary water cooled cylinder, formed with a base or flange 1^a in which are provided passages or channels 1^b leading to the water-jacket 1^c. The lower end 1^d of said cylinder 40 may project into the crank chamber 2 if a short water jacket is required.

Said cylinder 1 is provided with an inlet port 1^e and an exhaust port 1^f.

45 A broad groove is formed around said cylinder 1 to accommodate the broad ring 3 which is formed with inlet and exhaust ports (3^a 3^b Fig. 2) corresponding with those in the cylinder. Said ring 3 may be made in 50 two parts and the ends stepped or otherwise joined together, as shown in Fig. 2 in which a ring is shown in elevation, and valves 6 and 7 hereinafter referred to partly in section at 3^c, or, alternatively, the ring may be 55 a single piece. In either case the ring is free to expand.

A narrower groove is also cut in said cylinder 1 above the ports to accommodate the expansion ring 4, and a similar groove and ring 5 are provided below the ports, the object of said rings 4 and 5 being to expand 60 ring 3 and to prevent leakage of the gases by way of the back of said ring.

The inlet valve 6 and the exhaust valve 7 fit around cylinder 1. Said valves may be 65 formed by cutting a cylindrical sleeve in two vertical halves, each half forming one valve. Alternatively the valves may be made of sheet steel or other metal suitably pressed to shape. Each valve is provided with a 70 port 6^a and 7^a respectively. The inlet valve 6 is formed with a lug 6^b to which one end of the connecting rod 8 is pivoted, said rod being driven by the quarter-time valve-shaft 9. Similarly, the exhaust valve 7 is formed 75 with a lug 7^b and connected by the rod 10 to the quarter-time valve-shaft 11.

A valve cover 12 fits over the valves, said cover being provided with an inlet passage 12^a and an exhaust passage 12^b. The lower 80 end of the cover is provided with vertical flanges 12^c between which the inlet valve lug 6^b fits and is free to slide, and similar flanges 12^d are provided to accommodate the exhaust valve lug 7^b, this arrangement 85 preventing any tendency of the valves to turn around the cylinder. As a means of taking up wear, either flange may be formed with an adjustable piece, or if preferred the lug 6^b may be so provided. Said flanges 90 may be integral with the cover 12 or suitably secured thereto. Covers 12^b, 12^c may be fitted over the flanges.

Said valves are lubricated by admitting 95 oil through pipe 12^e to the groove 12^f.

The valve-shafts are driven from the engine shafts 13 through the medium of the worm gears 14, 15, 16, 17, 18 and 19 and the cross-shaft 20. Alternatively, any suitably form of toothed or chain gearing may 100 be employed for this purpose.

The travel of each valve is such that its port is moved alternatively over the upper and lower parts of the broad ring 3 the valve port registering with the cylinder 105 port on both its upstroke and its down-stroke. The result of this motion is that the ports are opened and closed during the most rapid part of the valve movement and also that during compression and firing the 110 valves are almost stationary as they are then traversing their dead centers.

As shown in Fig. 1 the piston 21 is at the end of its working stroke and the exhaust valve 7 (on its up-stroke) has begun to register with the exhaust port 1^f for the exhaust stroke. It will be seen that the maximum port opening will coincide with the greatest speed of the piston, while the angle of the valve shaft crank will make it clear that the opening and closing of the port will be rapid.

As the valves are positively driven the port opening and closing is exact at all speeds.

During compression and firing the valve ports are effectively sealed by the ring 3 on inside and by the pressure of the valves against the cover 12 on the outside. Said ring 3 also prevents leakage by way of the valve joints—the minute division between the edges of the valves. As hereinbefore mentioned said expansion rings 4 and 5 prevent leakage by way of the back of the broad ring 3.

A suitable packing ring or cover 12^e is provided at the cylinder top to prevent oil leakage.

Referring to the air cooled engine illustrated in Fig. 5, the valves are operated from one side, and lugs 6^b, 7^b are disposed centrally and connected to the quarter-time valve shaft 22 which is driven through worm or like gearing 23, 24. Flanges 12^c 12^d are provided in the cover 12 to accommodate both lugs 6^b 7^b.

Having now described my invention what I claim as new and desire to secure by Letters Patent is:—

1. In a four-stroke cycle internal combus-

tion engine, the combination with the working cylinder of a compression-holding ring, 41 its ends being suitably joined together, inlet and exhaust ports corresponding with those of said working cylinder provided in said ring, two or more expansion rings arranged on the back of said compression-holding ring, 45 separate segmental or half-cylindrical slide valves arranged to operate on both their up-stroke and downstroke, a valve cover, lugs formed on said valves, and flanges on said cover adapted to act as guides for said valve 50 lugs.

2. In a four-stroke cycle internal combustion engine, the combination with the working cylinder of a compression-holding ring formed in one or two parts, its ends being 55 suitably joined together, inlet and exhaust ports corresponding with those of said working cylinder provided in said ring, two or more expansion rings arranged on the back of said compression-holding ring, separate 60 segmental or half-cylindrical slide valves arranged to operate on both their up-stroke and down-stroke, lugs formed on said valve, a valve cover and flanges on said cover adapted to act as guides for said valve lugs, a 65 water jacket and a base or flange formed on the working cylinder, and water channels communicating with said jacket formed in said base or flange.

In testimony whereof I affix my signature 70 in the presence of two witnesses.

ARTHUR ALLTREE.
